(57) **CLAIM**

The ornamental design for a bathing suit bottom, as shown and described.

DESCRIPTION

FIG. 1 is a side, perspective view in accordance with a new bathing suit bottom design;

FIG. 2 is a front view of the design of FIG. 1;

FIG. 3 is a back view of the design of FIG. 1;

FIG. 4 is a left side view of the design of FIG. 1;

FIG. 5 is a right side view of the design of FIG. 1;

FIG. 6 is a top view of the design of FIG. 1;

FIG. 7 is a bottom view of the design of FIG. 1; and,

FIG. 8 is a side, perspective view of the design of FIG. 1 in a use environment.

The broken lines are included for purposes of illustrating environment and form no part of the claimed design. The portions of the article shown broken away with broken, zig-zag, cut-off lines in FIGS. 1 through 8 indicate that any portion of the article beyond what is shown forms no part of the claimed design.

1 Claim, 8 Drawing Sheets(56)
